P. DRESSLER.

TUNNEL KUN.

APPLICATION FILED JAN. 22, 1919.

1,384,434.

Patented July 12, 1921.

FIG. 2.

FIG. 3.

884 Wis.

By his Attorney
Geo H. Benjamin

UNITED STATES PATENT OFFICE.

PHILIP DRESSLER, OF ZANESVILLE, OHIO, ASSIGNOR TO AMERICAN DRESSLER TUNNEL KILNS, INC., OF NEW YORK, N. Y., A CORPORATION OF NEW YORK.

TUNNEL-KILN.

1,384,434.

Specification of Letters Patent. Patented July 12, 1921.

Application filed January 22, 1919. Serial No. 272,413.

To all whom it may concern:

Be it known that I, PHILIP DRESSLER, a subject of the Kingdom of Great Britain, residing at Zanesville, in the county of Muskingum, State of Ohio, have invented certain new and useful Improvements in Tunnel-Kilns, of which the following is a specification.

My invention relates to tunnel kilns of the type suitable for use in the manufacture of tiles, pottery and analogous ware, as also for other purposes, for example, annealing of glass and metals, enameling of metals, and the like.

The object of my invention is a construction by reason of which a better control and diffusion of the combustible vapor introduced is obtained, as also greater accessibility of the gas conveying pipes for cleaning and repair.

The accompanying drawings will serve to illustrate my invention, in which:

Figure 1 is a vertical transverse section through a kiln.

Fig. 2 is a vertical elevation and partial section through the vapor controlling valve, the view being taken at the left of Fig. 1.

Fig. 3 is a vertical section taken on the line III—III of Fig. 1.

In its main features, the kiln corresponds in construction with that shown in the prior patent of Conrad Dressler No. 1,170,428 dated Feb. 1, 1916, to which reference is made for further information as to the main features of construction. I wish it understood, however, that I do not limit myself in any wise to such construction, as my invention is applicable to any type of interiorly heated kiln.

In the drawings, the kiln shown consists of the inclosing chamber A, goods chamber B, combustion chambers C, hot air flues D surrounding the combustion chambers, and goods carriage E adapted to be moved through the chamber in any suitable manner. Arranged under the inclosing chamber is a horizontal flue E which leads from the source of gas supply. Connected to this flue on opposite sides of the outside of the kiln, are vertical flues G, and connected to these vertical flues and projecting inwardly into the combustion chambers, are burners H. The ends I of these burners are so disposed as to project a stream of gas horizontally into the combustion chamber C.

Situated within the vertical flues G are valves J having the shape of a truncated cone or other suitable shape. Each of these valves is supported by a nut K on the lower end of a rod L which passes through it, and which rod and valve may be lowered by means of a cable M carried over pulleys N and a drum O, provided with ratchet P and crank arm Q. By raising and lowering the valve J the flow of gas can be accurately regulated, and by allowing the valve to fall through the vertical flue G all of the soot in the flue may be quickly removed without any material interruption to the supply of gas to the burners H. As a means of collecting the soot removed from the vertical flues G, a basin R is provided under each flue. To facilitate cutting out the burner tube H, a damper S is provided in each vertical flue G. The door T may then be opened and a scraper introduced into the burner and the soot removed. Any other suitable means may be employed for removing the soot.

The advantage of the construction disclosed, is found in the fact that the gas supply can be exactly regulated, irrespective of the pressure at which the gas is supplied to the kiln, and the gas introduced into the combustion chambers in such manner as to bring about a perfect mixture with the heated air and free burning obtained without the gaseous vapor impinging upon the walls of the chambers. Further, the objection of clogging of the gas supply tubes common in furnace construction, is entirely done away with through the instrumentality of the falling weighted valve, which keeps the passages clean.

Having thus described my invention, I claim:

1. In a tunnel kiln and in combination with the combustion chambers, gas burners projecting into the combustion chambers through the sides of the latter and adapted to project a supply of gas in a horizontal direction along the combustion chambers, gas supply flues located exterior to the kiln and connected to the burners, and gas regulating valves between said gas supply flues and burners.

2. In a tunnel kiln and in combination with the combustion chambers, gas burners projecting into the combustion chambers through the sides of the latter and adapted

- 2
- to project a supply of gas in a horizontal direction along the combustion chambers, vertically disposed gas supply flues located exterior to the kiln and connected to the 5 burners, gas regulating valves between said gas supply flues and said burners, and means for adjusting the position of said valves. 10
3. In a tunnel kiln and in combination with the combustion chambers, gas burners projecting laterally into the combustion chambers and adapted to project a supply of gas in a horizontal direction along the combustion chambers, vertically disposed gas supply flues located exterior to the kiln and 15 connected to the burners, weighted gas regulating valves situated in the vertical gas supply flues, together with means whereby said valves may be moved to regulate the supply of gas and allowed to drop to remove 20 accumulations in the vertical flues. 25
4. In a tunnel kiln and in combination with the combustion chambers, gas burners projecting laterally into the combustion chambers and adapted to project a supply of gas in a horizontal direction along the combustion chambers, vertically disposed gas supply flues located exterior to the kiln and connected to the burners, gas regulating 30 valves between said gas flues and said burners, said gas regulating valves having the shape of a truncated cone, together with means for lifting and lowering said valves 35 to regulate the gas supply and also permit movement of said cones through the vertical flues to remove accumulations in said flues. 40
5. In a tunnel kiln and in combination with the combustion chambers, gas burners projecting into the combustion chambers through the sides of the latter and adapted to project a supply of gas in a horizontal 45 direction along the combustion chambers, vertical gas supply flues located exterior to the kiln and connected to the burners, gas regulating valves between said gas supply flues and said burners, and dampers in said vertical flues below the burners. 50
6. In a tunnel kiln and in combination with the combustion chambers, a horizontally disposed gas flue located below the chambers and the bottom of the kiln, vertically disposed flues connected to said horizontal flue and located exterior to the kiln, gas burners connected to said vertical flues projecting inwardly through the walls of the kiln and combustion chambers and 55 adapted to discharge in the interior of the combustion chambers in a longitudinal direction; gas regulating valves interposed between the vertical flues and the gas pipe, and means for controlling the movement of 60 such valves.

In testimony whereof, I affix my signature.

PHILIP DRESSLER.
